CALCULATING MACHINE

Harold T. Avery and Theodore H. Lassagne, Oakland, Calif., assignors to Marchant Calculating Machine Company, a corporation of California

Application December 1, 1943, Serial No. 512,452

2 Claims. (CL 235—145)

This invention relates to calculating machines and has particular reference to an improved keyboard mechanism for calculating machines of the key-set type, such as disclosed in the patent to Harold T. Avery, Number 2,216,659, issued on October 1, 1940.

The present invention is illustrated as applied to the Marchant calculating machine described in said patent and reference may be had thereto for a complete description of the machine, including mechanisms not specifically disclosed herein. However, it is to be understood that the invention is not limited to use in this machine but may be applied to any calculating or like machine wherein it is desired at certain times to prevent depression or release of any or all value keys.

In performing a series of machine calculations it often happens that certain digits of a factor set up on the keyboard are later repeatedly used in setting up other factors for succeeding calculations and the successive clearance and reinstating of such digits in the keyboard obviously entail waste time and effort. Also it is often desirable to retain one factor in one portion of the keyboard as a "constant" to be used in combination with changing factors set up on another portion of the keyboard.

In the copending application of Avery et al. Serial Number 435,806, filed March 23, 1942, a keyboard lock mechanism is disclosed and claimed which is capable of selectively locking the entire keyboard or only a part of the keyboard against clearance or entry of a value therein, thus making it possible to lock a constant in the keyboard for a succession of machine calculations while allowing other values to be set in the remainder of the keyboard and to be cleared after each problem. The mechanism is also capable of automatically preventing inadvertent clearance or change of a keyboard set-up during the performance of an automatic division operation whether or not the manually settable keyboard lock control means is effective. This mechanism is entirely practical in operation, however, it has the disadvantage that the locking of a value or constant in the keyboard has the effect of blocking the operation of a spring pressed keyboard clearing device and thus imposes a load on the keyboard clearing mechanism when the same is operated either manually or automatically to clear whichever keys are not locked.

The principal object of the present invention is to reduce the loading of a master keyboard

clear key in a mechanism of the type disclosed in the above mentioned application.

A further object is to obviate the need for a blocking device in a mechanism for preventing release of predetermined keys of the keyboard during release of the keyboard by a master keyboard releasing device.

10 A further object is to prevent loading of a master keyboard release device while at the same time preventing depression or release of keys in any key row of the keyboard.

15 The manner in which the above and other objects of the invention are accomplished will be readily understood on reference to the following specification when read in conjunction with the accompanying drawing, wherein:

20 Figure 1 is a side view, partly in section, of one bank or row of value selecting keys, illustrating, in part, the keyboard clearance controlling mechanism embodying the present invention;

Figure 2 is a fragmentary side view, similar to Figure 1, illustrating the keyboard clearance controlling mechanism in an alternative position;

25 Figure 3 is an enlarged transverse sectional view of one of the key banks and is taken substantially along the line 3—3 of Figure 1;

Figure 4 is a view similar to Figure 3; with parts broken away, and is taken substantially along the line 4—4 of Figure 1;

30 Figure 5 is a side view illustrating the selectively settable control means for the keyboard clearance control mechanism, and the means for superseding the manual control of the mechanism during an automatic division performance;

35 Figure 6 is a side view of the keyboard clear key mechanism.

In a machine designed for calculating in accordance with the decimal system, such as the one to which the mechanism of the present invention is applied, the keys are preferably arranged in a series of identical and juxtaposed banks of at least nine keys each, the number of banks depending upon the magnitude of the factors with which the machine is designed to deal.

40 The construction of each of the key banks or sections is substantially the same as disclosed in the Avery Patent Number 2,255,909, issued on September 16, 1941, and comprises the usual number of value keys 100, each of which is slidably mounted in a channel shaped key frame 101 fixed in the frame of the machine. Each key is normally maintained in a raised position by a compression spring 102, and the key stem 103 thereof is provided with a shoulder 111 (Figure

3) which is adapted to engage a stop 107 mounted on the respective channel frame 101 to limit upward movement of the key, while a projection 104 on the key stem is adapted to engage the lower leg of the channel frame 101 to limit depression of the key.

All of the key stems are of the same length and each has a cam extrusion 116 which, upon depression of the key, pushes to the right, as viewed in Figure 1, a slotted key locking slide 117 slidably supported on the under side of the channel frame 101 by studs 106 extending through elongated slots 107 formed on the lower leg of the key frame. Upon full downward depression of any value key, with the exception of the leftmost or zero key 100', the locking slide 117, which is urged leftward by a compressed spring 118 (Figures 1 and 3) extending between retaining fingers on the frame and the slide, snaps back into its initial location and by engaging over the upper end of the extrusion 116 latches the depressed key.

Disposed under each bank of value keys 1 to 9, inclusive, is a differentially settable bar 130 which is pivotally suspended from the key frame 101 by means of two parallel links 131 and 132. This bar 130 has nine identical V-notches 133 formed on the upper edge thereof, each of which merges at its bottom into a downwardly extending slot 134 adapted to receive the lower end of a corresponding key stem 103. The vertical center lines of the key stems 103 are spaced an equal distance apart. This distance, however, is slightly greater than the spacing between the successive equi-spaced slots 134 so that each succeeding slot 134 will be spaced one increment further away from its cooperating key stem. This spacing is so proportioned that depression of a value key will cam the bar 130 to the right, as viewed in Figure 1, a number of increments equal to the value represented by the depressed key.

Movement of each bar 130 is utilized to set up a mechanical representation of the selected value whereby the calculating mechanism may be accordingly controlled. For this purpose a swinging segment member 148 is pivotally mounted on a transversely extending shaft 149 supporting like members associated with other key banks. This member 148 is provided at opposite ends thereof with arcuate racks 150 and 151 which serve to transmit the movement of the differential bar 130 to different parts of the calculating mechanism and thus control the same accordingly. However, when no value key of a key section is depressed, the respective bar 130 is held in its extreme leftward or ineffective position, as illustrated in Figure 1, by a tension spring 152 extending between an ear 153 on the segment member 148 and a portion of the machine frame (not shown). When a bar 130 is allowed to remain in this position during a machine operation no direct entry of a value will be effected in the corresponding order of the accumulator.

The leftmost key 100' in each section is the zero or clear key and is provided for the sole purpose of releasing any latched down value key in the same section. The stem 103 and extrusion 116 of this key are identical with the other keys of the section, but latching down of the same is prevented by the provision, on locking slide 117, of a lip 119, the lower edge of which lies below the lowest position assumed by the top of the extrusion 116. Hence, while the slide 117 is moved to the right upon depression of this key to release any other latched down key, the lip 119 prevents the slide from returning leftward dur-

ing the depression of the zero key and latching thereof cannot be effected.

Master manual and automatic keyboard clearing means are provided which are capable of simultaneously releasing every depressed key on the entire keyboard, but which may be rendered ineffective with respect to any or all of the rows of keys as hereinafter described.

Describing first the manual keyboard clearing means, a clear key 122 (Figure 6), which is normally maintained in a raised ineffective position by a spring 123, is guided for vertical movement by a link 140, pivoted at one end to the stem of key 122, and at the other end on a frame pin 141, the lower end of the key stem being provided with a slot 142 embracing a second frame pin 143. A roller 124 is mounted on the key stem and overlies a curved finger 144 forming part of a keyboard clear bail 125, pivoted at its ends on frame pins 126.

As described in detail in the above mentioned Avery Patent Number 2,216,659, means are also provided for automatically clearing the keyboard during addition or subtraction operations. To this end a bar 179 (Figure 6), identical with the correspondingly numbered bar of said patent, is provided with a bifurcated end embracing a pin 781 on the finger 144. During an addition or subtraction operation, the bar 179 is automatically reciprocated to rock the finger 144 and thereby rock the key release bail 125 in the same manner as does the depression of key 122.

According to the present invention, means are provided for locking any or all depressed keys to prevent their release, or for preventing depression of any or all keys. This locking means offers considerable flexibility in operation, being adapted to be set to lock a constant of any desired number of digits in any part of the keyboard while allowing the remainder of the keyboard to remain free to receive other digits and to be cleared, or to lock the entire keyboard against entry or clearance of a value therein, or to automatically lock the keyboard against inadvertent or inadvertent entry or clearance of a value during division regardless of the manual setting of the locking mechanism without disturbing such manual setting.

In accordance with the present invention the keyboard clear bail 125 carries a plurality of pivotally mounted interponent devices 195; one of said devices being situated adjacent the forward end of each of the locking slides 117 upon a pivot 196 carried by an ear extending from bail 125. A cooperating fulcrum and blocking lever 156 (Figures 1, 2, 3, and 4) is provided in each key row, being pivotally supported at one end on a stud 154 fixed to the wall of the channel frame 101. Each lever 156 is normally pressed against a washer 155, secured to the end of the stud 154, by a compression spring 157 fitted over the stud 154 and compressed between the lever 156 and a flange 158 formed on the stud so as to maintain the lever in the plane illustrated in Figure 3. The bearing formed in the lever 156 and fitting over the stud 154 has, however, sufficient clearance to allow a slight amount of sidewise rocking movement of the lever against the action of the spring 157, the reasons for which will appear hereinafter, while a light tension spring 160 is tensioned between the lever 156 and the lower leg of the key frame 101. Spring 160 has enough strength to rock the lever 156 downwardly to the lowermost dot and dash line position 156b (Figure 1), against the frictional resistance created by

the spring 157, if otherwise permitted to do so. However, if the lever 156 is of sufficient weight to rock downwardly of its own accord, the spring 160 may be omitted.

The foremost edge of each lever 156 has a series of surfaces disposed at different radial distances from the pivotal mounting of the lever and which, depending upon the rocked position of the lever 156, serve to fulcrum the interponent devices 195 of the keyboard clearing mechanism and also, preferably, to prevent movement of the associated locking slide 117 under certain conditions to be described. Two of these surfaces designated 192 and 193 are concentric with the stud 154 and are disposed at the same radial distance from the center thereof. These surfaces are adapted, when the lever 156 is in either of two alternate "fulcruming" positions illustrated in full and in dot-dash lines, respectively, in Figure 1, to act as a fulcruming surface for an ear 194 of the opposite one of the series of interponents 195. This arrangement is such that when the ear 194 engages either of the surfaces 192, 193, the lower end of the interponent 195 will engage a downwardly bent leg 197 formed on the associated locking slide 117. Thus with the lever 156 in either of its "fulcruming" positions, clockwise rocking of the clear bail 125, as by depression of the master clearance key 122, will cause the interponent to fulcrum on whichever surface 192 and 193 it is opposite, and the lower end of the interponent will then engage and move the locking slide 117 rearward to release any depressed key in the associated key row.

However, when the lever 156 is in either of two "intermediate" positions illustrated in Figure 2, a notch 200 formed in the forward edge of the lever intermediate the sections 192 and 193 will be located opposite the ear 194. Therefore, when the gate 125 is rocked clockwise the interponent will merely fulcrum on the lug 197 of the locking slide without moving the same and the upper ear 194 will rock into the notch 200.

In order to limit clockwise movement of the bail 125 beyond that necessary to cause release of the locking slide 117 when the lever 156 is in either of its fulcruming positions illustrated in Figure 1, and also to prevent fulcruming of the interponent 195 on the bottom of the notch 200 in such a manner as to effectively move the slide 117 when the bail 125 is rocked with the lever 156 in either of the intermediate positions illustrated in Figure 2, an adjustable stop is provided comprising a stop screw 198 threaded through the upper part of the bail 125 and adapted to abut the end of a notch formed in a cross bar 199. Bar 199 also forms part of the frame of the machine and supports the forward ends of the various key frames 101.

As shown in Figures 1 and 2, the outer depending leg of the lever 156 is formed to extend through an opening 161 in the key locking slide 117 and has a lobe 162 (Figure 2) formed therein which, when the lever is in either of its intermediate positions illustrated in Figure 2, lies directly behind the foremost edge of the opening 161 and thus blocks rightward key releasing movement of the slide. Therefore, all of the keys in the associated key section will be locked in their current raised or depressed position so that they cannot be released by depression of the zero key 100' or any of the other keys 100 of the row. It will also be noted that whenever the latching slide 117 is blocked by the lever 156, the bail 125 is ineffective to cause the interponent 195 to

exert pressure on that particular slide by virtue of the alignment of the notch 200 in the member 156 with the ear 194 of the interponent 195.

Means operable in conjunction with the differentially settable bars 130 are provided to control the positioning of the individual levers 156 and thereby control the selection of the several modes of operation mentioned hereinbefore. This means comprises a rockable bail 165 common to all of the members 156 (Figures 1, 2, and 5) and adapted to be set in any of three different positions to limit counterclockwise movement of all of the levers 156 accordingly. The bail extends across the entire keyboard and passes through openings 101a in the walls of the various key frames 101. Ears 166 are formed on the opposite ends of the bail 165 and are pivoted on coaxial frame pins 167. One of the ears 166 (Figure 5) is suitably secured to an arm 168 connected by a link 169 to a lever 171 which is pivoted at 172 to a settable control lever 173.

The lever 173 is pivoted on a frame stud 174 and has a portion thereof extending through a slot in the keyboard cover plate so that it may be adjusted by the machine operator into any one of three positions indicated at A, B, and C.

Detent means are provided to hold the lever 173 in any of its three positions, comprising a pawl 175 pivoted on a frame pin 176 and urged counter-clockwise by a spring 177 tensioned between the pawl and a frame pin (not shown). The pawl has three spaced notches formed therein each of which is adapted to engage a pawling projection 173' formed on the lever 173 when the latter is in one of the positions described.

The lever 171 is provided with a pivot pin 178 intermediate its ends, which pin extends into an opening 180 in a combined camming and pivot lever 181, which is pivotally supported on a frame pin 182. The lever 181 is connected to a division initiating key 970 through a train of elements comprising a link 183, arm 184 fastened to a rockable shaft 1256 to which is also fastened a lever 1026, and a link 965 connecting the lever 1026 to a key supporting lever 973 which is pivoted on a frame pin 974. The lever 973 and a link 972 form a parallel link arrangement for guiding the key 970 in a substantially vertical direction during depression of the key or release thereof from depressed position.

The division key 970 is normally held in its illustrated raised position by spring means not shown. However, upon depression thereof to a position wherein an ear 980 on the supporting lever 973 is engaged by latching shoulder 981 of a spring pressed latch 982, a division operation will be initiated as described in detail in said Avery Patent Number 2,216,659. The division operation will automatically continue until it is terminated either automatically or by depression of a special "stop" key, at either of which times the latch 982 will be rocked down to allow the key 970 to again be spring raised to its upper position.

Assume for the present that the key 970 is allowed to remain in the raised position in which it is illustrated so that the lever 181 is positioned to embrace the pivot pin 178 in a narrow upper guide slot 188, forming part of the opening 180 thereof, forming a fulcrum for the lever 171.

With the lever 181 positioned, as illustrated, movement of the lever 173 to its "ineffective" position A, will cause the lever 171 to rock about the axis of pin 178 and cause the link 169 and arm 168 to move bail 165 to its highest rocked position shown in Figures 1 and 5, and the bail

will engage and rock all of the levers 156 to the position shown in Figure 1 wherein its blocking surface 162 is situated above the level of the associated locking slide 117 and, therefore, cannot prevent release or depression of any of the keys in the keyboard, while the surface 193 thereof is positioned to fulcrum the interponent 195 during operation of the keyboard clearing bail 125 causing the lower end of each interponent to move its associated slide 117. The keyboard clearing mechanism will therefore function in the usual manner.

Movement of the lever 173 to its intermediate or "full keyboard lock" position B will cause the lever 171 to rock on its pin 178 until its pivotal connection 170 assumes a position B' whereupon the bail 165 will be positioned at an intermediate height indicated by the dot and dash lines 165' (Figure 2). When the bail 165 is in this position, the springs 160 in all of the key banks of the keyboard in which no value key has been depressed will be allowed to rock their respective levers 156 downward to the position illustrated by the dot and dash lines 156a, wherein the blocking lobes 162 on the levers 156 will be positioned in blocking relation with the forward edges of the openings 161 of the key locking slides, thus preventing depression of any raised key or release of any depressed key. In each of those orders in which a key has already been depressed and latched in depressed position before movement of lever 173 to position B, the key stem of the depressed key will have cammed the differentially settable bar 130 to the right, as viewed in Figures 1 and 2. Thus, an ear 190 formed on the bar 130 will be moved into blocking relation with the lowermost offset end 191 of the lever 156 and will hold the lever 156 at its upper intermediate position illustrated in full lines in Figure 2 wherein the lobe 162 thereof will also be located in blocking relation with the forward edge of the opening 161 in the associated slide 117. Therefore, any value set up on the keyboard and locked therein by movement of the lever 173 to its intermediate position B will be retained therein and cannot be changed or cleared until the lever 173 is again rocked out of this position. It will be noted that when levers 156 are in either of the two positions illustrated in Figure 2, the ears 194 of interponents 195 will enter the notches 200 preventing the transmission of any force from bail 125 to any slide 117 associated with a lever so set.

Movement of the lever 173 into its rearmost "keyboard-constant lock" position C will cause the lever 171 to rock on its pin 178 until the pivotal connection 170 assumes a position C', at which time the bail 165 will be moved to its lowermost possible position indicated by the full lines in Figure 2 and the dot and dash lines in Figure 1. When in such position, the springs 160 in all key sections of the keyboard in which no value key has been depressed will be allowed to rock their respective levers 156 downward to their lowermost possible positions illustrated by the dot and dash lines 156b in Figure 1, carrying their blocking lobes 162 below the level of the associated locking slides 117 wherein they will be ineffective to prevent releasing movement of those slides. However, in each of those orders in which a key has already been depressed and latched in depressed position before movement of lever 173 to position C, the key stem 103 of that key will have cammed the associated differentially settable bar 130 to the right and the ear 190 on the bar 130 will have moved into blocking relation

with the lowermost offset end 191 of the lever 156 and will hold the lever in its upper intermediate position shown in full lines in Figure 2. Thus, the lobe 162 on that lever will again be located in blocking relationship with the associated slide 117.

It should be noted that the ear 190 is so arranged on each of the bars 130 that when the bar is held in its "zero" position, illustrated in Figure 1, by the spring 152, the ear 190 will not interfere with movement of the lever 156, and it is only when the number "1" or higher value key is depressed that the ear 190 is moved into blocking relation with the corresponding lever 156, such a situation being illustrated in Figure 2 wherein the "2" value key is depicted as latched in depressed position.

It will be seen from the above that a value or constant may be locked indefinitely in the keyboard while permitting other values to be set in the keyboard and then cleared in the usual manner; the interponents 195 fulcruming on the surfaces 192 of all fully lowered levers 156. This may be accomplished by first setting the lever 173 in its ineffective position A, if it is not already there, and then setting up the value or constant which it is desired to retain indefinitely. Thereafter, the lever 173 is moved to its "keyboard-constant-lock" position C, and, consequently, the levers 156 in those orders in which no value key has been depressed will drop to their lowermost ineffective positions while the levers 156 in those orders in which a key is depressed and latched will be blocked by the ears 190 of the respective differential bars 130, thereby holding such levers in blocking relation with the corresponding key locking slides 117. However, in the event that all of the keys are in raised position prior to such setting and locking of a value in the keyboard or

in the event that it is desired to set and lock a value in the keyboard in addition to a value or constant already locked in the keyboard, the lever 173 may be left in position C during the depression of the keys to be locked. The lever 173 would then be moved to its position A and thence back to position C, resulting in all of the depressed keys being locked in depressed position.

During such movement of the lever 173, value keys will be standing in a depressed position in key sections wherein the blocking levers 156 were originally allowed to drop to their lowermost positions. The blocking ears 190 of the corresponding differential bars 130 will, therefore, be situated over the offset ends 191 of the blocking levers 156, and as the control lever 173 is rocked to position A, the inclined left surfaces (Figure 3) of the offsets 191 on the levers 156 will merely cam the levers sideways as they pass upward past the ears 190. At this time, the springs 157 on the pivot studs 154 will merely yield until the offsets 191 pass above the ears 190 at which time the springs 157 will snap the levers 156 into their original illustrated vertical planes, again positioning the offset ends 191 directly over the paths of movement of the ears 190. When it becomes desirable to release any key or keys locked in depressed position, the lever 173 is merely moved back to its ineffective position A and any of the several clearing means may be operated to release the keys.

Depression of the division key 970 to initiate a division operation will cause the bail 165 to assume its intermediate "full keyboard lock" position 165' (Figure 2) regardless of the setting of the lever 173 and without changing such setting,

and will therefore lock the entire keyboard. When the division key is allowed to rise at the completion of the division operation, the keyboard will again be restored to the particular locked or unlocked condition previously determined by the setting of the lever 173. To this end, the opposite edges of the opening 180 in the lever 181 converge downwardly into a narrow slot 194 capable of embracing the pivot pin 170 extending from the lower end of the lever 171. The opening 180 in lever 181 is so formed that, upon depression of the division key 970 to its lowermost latched position and consequent upward rocking movement of the lever 181 to the position illustrated in part by dot and dash lines 181' (Figure 5), the upper converging sides of the opening 180 will free the pivot pin 170 on lever 171, while the lower converging sides of the opening will cam the lower pivot pin 170 into the narrow guide slot 194. This slot is arranged so as to locate the pin 170 substantially in the position B' regardless of the setting of the lever 173, and therefore the bail 165 will be moved to its intermediate position 165' (Figure 2) to hold all of the levers 156, with the exception of any such levers which have been blocked in the full line position indicated in Figure 2 in the manner described hereinbefore, in their blocking positions 156a. It should be noted that since this latter position 156a is below the full line position illustrated in Figure 2, the bottom offset edge 191 of such levers will be located below the upper edge of the blocking ears 190 of the differentially settable bars 180.

Upon termination of the division operation, the division key will be spring pressed upwardly to its original position and the lever 181 will resume the lower position in which it is shown in full lines, during which time the lower converging edges of the opening 180 will free the pin 170 while the upper converging edges of the opening will cam the pin 170 into the slot 186, causing the lever 171 and bail 165 to assume their originally set positions in accordance with the setting of the lever 173. Of course, if the lever 173 was originally set at "B" before depression of the key 970, movement of the camming lever 181 from its normal position and back again will not cause movement of the lever 171 or the elements (including bail 165) connected thereto. 50

If, however, the lever 173 was originally set at "C," automatic release of the division key 970 to its raised position at the end of division with consequent rocking of the ball 165 from the dot and dash line position indicated at 165' of Figure 2 to its full line position therein, will allow those levers 156 which are not blocked by the corresponding ears 190 to resume their lowermost unblocking positions 156b (Figure 2) which they occupied before the depression of the division key 970. Therefore, movement of the key 970 to its raised position will effect restoration of the keyboard to the same locked or unlocked condition that it occupied prior to the division operation.

15 We claim:

1. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means.
- 20 2. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means.
- 25 3. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means, a selectively settable device, and means controlled jointly by said settable device and by said keys upon depression thereof for selectively adjusting said fulcruming and blocking member.
- 30 4. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means, a selectively settable device, and means controlled jointly by said settable device and by said keys upon depression thereof for selectively adjusting said fulcruming and blocking member.
- 35 5. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means, a selectively settable device, and means controlled jointly by said settable device and by said keys upon depression thereof for selectively adjusting said fulcruming and blocking member.
- 40 6. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means, a selectively settable device, and means controlled jointly by said settable device and by said keys upon depression thereof for selectively adjusting said fulcruming and blocking member.
- 45 7. In a calculating machine having a keyboard comprising a row of depressible keys and means for holding a depressed one of said keys in depressed position; releasing means for moving said holding means to release said depressed key comprising the combination of a clearing member with means comprising a lever pivotally mounted on said clearing member and a fulcruming and blocking member selectively adjustable either to concurrently fulcrum said lever and permit unobstructed movement of said holding means thereby or to concurrently permit unobstructed movement of said clearing member and block movement of said holding means, a selectively settable device, and means controlled jointly by said settable device and by said keys upon depression thereof for selectively adjusting said fulcruming and blocking member.
